CLAIM

The ornamental design for a record player, as shown and described.

DESCRIPTION

FIG. 1 is a front, top perspective view of a record players design showing my new design.

FIG. 2 is a front view of the record players.

FIG. 3 is a rear view of the record players.

FIG. 4 is a left side view of the record players.

FIG. 5 is a right side view of the record players.

FIG. 6 is a top view of the record players; and,

FIG. 7 is a bottom view of the record players.

The surface shading is not a feature of the design but is utilized to illustrate the surface contour of the record player design in the drawings.

The broken lines in the drawings depict portions of the record player and form no part of the claimed design.
